(57) **CLAIM**

I claim the ornamental design for a rack for disposable bags, as shown and described.

DESCRIPTION

FIG. 1 is an isometric view of my rack for disposable bags showing my new design;
FIG. 2 is a left side elevation thereof;
FIG. 3 is a front view elevation thereof;
FIG. 4 is a right view elevation thereof;
FIG. 5 is a plan view thereof;
FIG. 6 is a bottom plan view thereof; and,
FIG. 7 is a side view of the rack in shipping and storage configuration.
